UNITED STATES PATENT OFFICE.

FRANCIS X. HOOPER AND WILLIAM HOLLINGSWORTH, OF BALTIMORE,
MARYLAND, ASSIGNORS TO F. X. HOOPER & CO., OF SAME PLACE.

MACHINE FOR PRINTING ON BOARDS.

SPECIFICATION forming part of Letters Patent No. 359,972, dated March 22, 1887.

Application filed August 13, 1886. Serial No. 210,790. (No model.)

To all whom it may concern:

Be it known that we, FRANCIS X. HOOPER and WILLIAM HOLLINGSWORTH, citizens of the United States, residing at Baltimore, in 5 the State of Maryland, have invented certain new and useful Improvements in Machines for Printing on Boards, of which the following is a specification.

This invention relates to a printing-machine 10 for printing upon boards with two colors in one continuous operation.

One description of boards which are to be printed by this machine are used for the ends of boxes, such boxes as are employed for 15 packing goods of various kinds, notably canned goods—such as oysters, fruits, &c. Instead of stenciling upon the end of the ready-made box to denote its contents, the board designed for the box-end is printed previous to being made up into the box. Where 20 boxes are made up in large numbers for packing special articles, this plan is found more economical, besides producing neater and better work. Another kind of boards which may 25 be printed to advantage are those used for advertising-signs.

The invention is illustrated in the accompanying drawings, in which—

Figure 1 is a side elevation of the machine. 30 Fig. 2 shows two views of the cylinder adjustment. Fig. 3 is a section, on a somewhat smaller scale, showing the upper works supported on the upright impression-screws. Fig. 4 is a vertical longitudinal section of the 35 machine. Fig. 5 is a plan view of the upper feed mechanism and side guides. Fig. 6 is a top plan of the machine.

The letter A designates the frame and table; B, the drive-pulley. This machine has two 40 type-cylinders, C C', both mounted in a movable frame, D, above the table. Each cylinder is designed to work a different-colored ink, so that a board, a, passing below the cylinders, will receive an imprint of two colors. 45 Two ink-receptacles, b b', are provided above the cylinders, and two sets of ink-distributing rollers, c c', of suitable or well-known construction in printing-machines, are also provided. The cylinders and inking mechanisms

are mounted on the movable frame D, which 50 is supported on four upright screws, d, each of which has its lower end fitted to turn in a box-bearing, e, (see Fig. 3,) on the main frame A, and each screw has a fixed collar, f, which is seated on the said frame A. These collars 55 sustain the screws, which, as stated, may turn in the bearing e. Below the bearing e each screw has a spiral spring, g, and a nut, g'. By this construction the screws are immovable downward, but may yield upward. The 60 four screws are connected with the movable frame D by screw-threads and boxes h on the frame. All the screws have their upper ends in a square frame, h', and each screw has at its upper end a chain-wheel, i, and all of the 65 chain-wheels are connected by an endless chain, i'. One of the screws has at its upper end a hand-wheel, d', by turning which the connecting-chain i' causes all the screws to turn, and in this way the said movable frame 70 D and all the upper works on it may be raised or lowered to adjust the type-cylinders C C' to suit the thickness of the boards, a, which are to be printed. It will thus be seen that while the entire upper works may be raised or lowered by turning the hand-wheel d' the said 75 upper works, after being adjusted, may also, by virtue of the springs g, yield somewhat in an upward direction to allow for ordinary variations in the thickness of the boards. 80

Each type-cylinder is to have attached to it, by any suitable means, the die k, which supplies the imprint. Below each cylinder is a supporting-roller, l, and between these two rollers l is a fluted roller, m, below the surface 85 of the table, which extends across the machine. This fluted roller is part of the feed mechanism, and bears against the lower side of the board a to carry it from the first cylinder, C, to the second cylinder, C'. 90

Two feed-rollers, each having an elastic face, n, bear down on the upper side of the board a, so that the board is between the lower roller, m, and the two upper ones, n. The two upper rollers, n, (see Fig. 5,) are narrow, and each 95 bears on the surface of the board a along one edge. These rollers are made of metal, n', and have a rubber ring, n, around the metal part.

The rubber-ring part comes in contact with the board, and as it has a good grip thereon the feed movement of the board is insured, and the rollers avoid defacing the imprint 5 made by the first cylinder. This feed mechanism may be termed the "secondary feed."

The two feed-rollers *n* are both on a single shaft, *o*, which is driven by a pinion, *o'*, and the rollers may slide so as to be adjustable on 10 the said shaft. Each roller also turns in an outside bearing, *p*, which is fixed on a side guide, *q*, which latter guides or directs the board *a* straight from the first cylinder, *C*, to the second one, *C'*. The two guides *q* are 15 parallel, and are adjustable toward or away from each other, and when their adjustment is changed they carry the feed-rollers *n* with them, so that the adjustment of both is changed at one operation. Each guide *q* has a shank, 20 *q'*, at right angles with it, and the said shank part fits and moves in a groove, *r*, fixed to the table *A*. A set-screw, *r'*, on each guide-shank retains the guide wherever it may be set.

An adjustable receptacle for the board *a* is 25 on top of the machine-table *A*. (See Figs. 1, 4, and 6.) This receptacle consists of knee-pieces *E*, one side of which is fitted to slide in a groove on the table-top, and the other side stands upright. The boards *a*, preparatory 30 to going under the cylinder *C*, are placed or piled up in this receptacle. The bottom board of the pile is the one fed under the cylinder, and the feed mechanism to effect this may be termed the "primary feed," and consists of a 35 pusher-block, *F*, fitted in a longitudinal slot, *F'*, in the table-top. This pusher-block is connected with a horizontal rod, *G*, which is also attached to a second block, *G'*. At the bottom of the frame is a rock-shaft, *F''*, carrying an 40 upright arm, *H*, the upper end of which is connected with the second block, *G'*, by a link-rod, *I*. It will thus be seen that the rocking of the shaft *F''* will impart a reciprocating movement to the pusher-block *F*, and every time this 45 latter moves toward the cylinders *C C'* the bottom board in the receptacle will be forced under the first roller.

The rock-shaft *F''* has on one end a second arm, *J*, and a crank, *L*, is on a shaft, *L'*, while 50 a rod, *N*, connects the said arm *J* with the crank. This mechanism gives motion to the primary feed. It is necessary to be able to adjust this mechanism so that the pusher-block *F* may have a movement suited to the particular size of the board to be printed. To this end the crank *L* is made adjustable on its 55 shaft. The crank-arm has a split-collar part, *s*, and a screw, *s'*, therein serves to permit of the crank-arm being turned on the shaft and 60 set thereon at any point desired. This adjustment serves the purpose last above indicated.

The two cylinders are geared to run in unison; but it is important to be able to adjust 65 them with respect to each other after the

printing dies *h* have been attached, in order that the two colors may be properly imprinted or registered on the surface of the board *a*. This is effected by the devices seen in Figs. 1 and 2. The shaft *t* of the second cylinder, *C'*, 70 has a gear-wheel, *u*, by which it is turned. This gear-wheel turns loosely on the said shaft. A head, *v*, is keyed fast to the said shaft *t* and is close to the gear-wheel *u*. Several clamp-plates, *w*, are loosely attached to the 75 gear-wheel *u*, each one by means of a screw-bolt, *x*. The gear-wheel *u* is at one side of the head *v*, and the several clamp-plates *w* are at the other side. In other words, the rim of the head *v* is between the gear-wheel *u* and 80 the clamp-plates *w*. By turning the screw-bolts *x* the loose clamp-plates *w* are made to bind or grip the rim of the head *v*, and thereby the loose-turning gear-wheel *u* becomes fixed. It will be seen it is simply necessary 85 to loosen the clamp-plates *w*, then set each of the two cylinders to its proper position, and finally tighten the screw-bolts *x*.

Having described our invention, we claim and desire to secure by Letters Patent of the 90 United States—

1. In a machine for printing boards in two colors at one operation, the combination of two type-cylinders, *C C'*, each for a different color, both cylinders and their inking devices 95 being mounted in the same yielding frame, as set forth.

2. In a machine for printing boards in two colors at one operation, the combination of two type-cylinders, a movable frame on which 100 the cylinders are mounted, and upright screws for supporting the movable frame, as set forth.

3. In a machine for printing boards in two colors at one operation, the combination of two type-cylinders, a movable frame on which 105 the cylinders are mounted, upright screws for supporting the movable frame, and springs, *g*, to allow the upright screws to yield upward, as set forth.

4. In a machine for printing boards in two 110 colors at one operation, the combination of two type-cylinders, a movable frame on which the cylinders are mounted, upright screws for supporting the movable frame, a chain-wheel on each screw, and an endless chain connecting all the chain-wheels, as set forth.

5. In a machine for printing boards in two colors at one operation, the combination of two type-cylinders and two narrow feed-rollers 115 between the said two cylinders, each of which bears on the surface of the board which is passing through to be printed along one edge only, for the purpose set forth.

6. In a machine for printing boards in two colors at one operation, the combination of 120 two type-cylinders and elastic-face feed-rollers between the said two cylinders, for the purpose set forth.

7. In a machine for printing boards in two colors at one operation, the combination of 125

two type-cylinders and side guides, *q*, for the boards, located between the said two cylinders, as set forth.

8. In a machine for printing boards in two colors at one operation, the combination of two type-cylinders, side guides, *q*, for the boards, located between the said two cylinders, and a feed-roller on each guide, as set forth.

9. In a machine for printing boards in two colors at one operation, the combination of two type-cylinders, side guides, *q*, for the

boards, located between the said two cylinders, a feed-roller on each guide, and a single drive-shaft for the two feed-rollers, as set forth.

In testimony whereof we affix our signatures ¹⁵ in the presence of two witnesses.
